TYPEWRITER

Robert G. Clark, Brooklyn, N. Y., assignor to
J. William Mengel, New York, N. Y.

Application October 8, 1931, Serial No. 567,597

19 Claims. (Cl. 197—55)

This invention relates to typewriters and particularly, to that type wherein the characters are carried on a type cylinder, the particular character to be printed being selected automatically on the operation of the proper key.

My invention contemplates the provision of a comparatively simple and inexpensive typewriter comprising a minimum number of parts, in which type carrying bars are eliminated, which is comparatively noiseless in its operation, which prints by pressure instead of by hammer-like blows of the type, and which is compact and readily foldable and of comparatively little weight, whereby it is ideally suited for use where portable machines are required. The various objects of my invention will be clear from the description which follows, and from the drawings, in which,

Fig. 1 is a top plan view of my improved machine as it appears unfolded and ready for operation.

Fig. 2 is a rear view and partial vertical section of a part of the machine showing, particularly, the carriage feed or escapement, and the means for capitalizing and decapitalizing.

Fig. 3 is an enlarged top plan view similar to Fig. 1 and partly broken away of about half of my new machine.

Fig. 4 is a vertical section of the same in the unfolded position thereof, showing the folded or collapsed position in dotted lines, and

Fig. 5 is a vertical section taken on the line 5—5 of Fig. 3 showing the type cylinder and part of the means for supporting and operating the same.

In general, my new machine includes a type cylinder on which is provided a series of rows or lines of type comprising all of the necessary type characters, both upper and lower case. The desired character is selected by the depression of a key, whereby the cylinder is raised to select the proper row in which the selected character lies, the cylinder being also rotated to bring the selected character into printing position, and the entire cylinder being rocked to a very slight degree forwardly to print the character thus selected by pressure through a ribbon of the usual type.

The rows or lines of type characters are so designed that one-half of each row or line carries lower case characters, while the other half carries upper case characters, or characters designated on the rear half of each key. The change from upper case to lower case characters and vice versa is made by operating a capitalizing and

decapitalizing key. A suitable escapement feed for the carriage is provided as well as the usual ribbon mechanism. The parts are so supported and arranged that the key levers may be collapsed relatively to the remainder of the machine, and so that the entire machine may be folded up into a comparatively small space to render it readily portable.

In that practical embodiment of my invention which I have illustrated by way of example, I prefer to provide a foldable case for the machine, which case is normally opened up to bring the various parts into operative position. As illustrated, the case comprises three sections hinged together. The main section 10 includes the bottom 11, the rear wall 12, and side walls terminating in the upper curved edges 13. To the main section 10 is hinged, as by means of the hinge 17, the front section 14 which includes the wall 15, which becomes when folded, part of the front wall of the case, and the side walls 16.

The rear portions 18 of the side walls 16 are preferably offset inwardly of the remaining portions of said walls, as clearly shown in Figs. 1 and 3 and up to the dotted line 19 of Fig. 4, 25 whereby said portions 18 may be collapsed into position inwardly of the side walls of the main section when the front section is swung about the hinge 17. In this position, the limiting line 19 of the offset engages the curved upper edge 30 13 of the side walls of the main section.

The entire key board is also collapsed at the same time into the dotted line position shown in Fig. 4, as will be later described in detail. To the rear wall 12 of the main section is hinged the top section 20 as at 21. Said top section comprises the bottom wall 22 which becomes the top wall of the folded case, the wall 23 which becomes the rear wall of the folded case, and the wall 24 which becomes part of the front wall of the folded case and forming the continuation of the wall 14 of the front section for that purpose. It will be understood that the edge 25 is shaped to correspond to the shape of the upper edge 13 of the side walls of the main section, 45 and to correspond with the upper edge 26 of the side walls 16 of the front section. It will also be understood that suitable latches may be provided to secure the sections 20 and 14 together in their folded positions and that a suitable handle or other means by which my improved machine may be carried about in its folded position may be provided.

My improved machine may be removably fitted into the case though it will be understood that 55

if desired, the case may be used as part of the machine frame, or to support certain parts. In any case, the various parts of the machine are supported by a suitable frame designated generally by the numeral 30, said frame being provided with suitable bearings, brackets, lugs, arms and the like to support the various movable parts, as will be seen as this description progresses.

An extension on the frame as 31 serves to support the carriage 32 and the parts carried thereby. To form a guide way for the carriage, a suitable angle plate as 33 is secured to the extension 31 so as to form the groove 34 therebetween for the reception and guidance of the rear edge portion of the carriage. Similarly, the angle plate 35, secured to another extension or ear 36 of the frame forms the groove 37 therebetween to support and guide the front edge of the carriage. The platen 38 of the usual type is supported by means of the brackets 39 secured to the carriage 32, and is provided with a knob 45 for rotating the platen manually. Said brackets 39 further support the feed screw 40 which is rotatably held therein, and which terminates in the disc 41 provided with a series of spaced stop pins as 42. A spring as 43 provided with a suitable recess 44, is secured to the bracket 39, one of the pins 42 at all times entering the recess 44 for preventing normally any rotation of the feed screw. However, the screw may be readily rotated in either direction by means of the knob 41 since the rounded pins leave the recess 44 of the spring when said knob is rotated and re-engages the next one of the series of pins 42 to again retain the screw in the new position in which it is set. Manual rotation of the feed screw serves to feed the carriage in either direction, this movement being intended to be used for short distances at a time, and to obviate the necessity for disconnecting the carriage feed from the carriage. The feed screw operates through the internally threaded sleeve 71 which is normally held against rotation by the escapement mechanism 52, and which is prevented from moving longitudinally by means of the ears 79.

Paper is fed on to the platen through the groove 46 between the paper guide plate 47 and the platen, forwarding of the paper being assured as the paper passes between and is frictionally engaged by the paper rolls 48 and 49. The entire carriage is normally drawn toward the right in the usual manner by means of the flat spring 50, secured to the lower end of the left bracket 39, and coiled and placed under tension by means of the spring reel 51 pivoted to the frame of the machine. Movement of the carriage under the influence of the spring 50 is, however, normally prevented by means of a suitable escapement designated generally by the numeral 52 and which will later be described in detail.

As has been previously indicated, the type characters are carried on a suitable type cylinder 53 in vertically spaced rows or lines as 89, 90. Any desired number of such rows may be provided, but I have illustrated eight, which I have found to be sufficient to carry all of the characters required. Each of the rows as 89 and 90 may contain ten or twelve characters in all. One-half of the row, that is, through a circumference of 180°, 70 contains what I will term the lower case characters, while the other half of the row contains the upper case characters. Each of the keys 55 is adapted to select the desired character from either half of the row, but means are provided 75 to rotate the type cylinder through 180° so that

a key will select either an upper case or a lower case character, as the case may be, depending on the initial position to which the cylinder has been shifted by the shift, or capitalizing and decapitalizing key. It will be understood that the cylinder is always returned to either one of two initial positions when the operating key is released, said positions being the initial position for the selection of lower case characters, wherein the first lower case character is in printing position, or the initial position for the selection of upper case characters, wherein the first upper case character is in printing position.

The type cylinder is capable of three different movements. One of the movements is a substantially vertical or axial movement whereby the proper row or line is selected; the second movement is that whereby the proper character in the selected row is selected by the rotation of the type cylinder about its axis, and the third movement is that wherein the type cylinder is tilted bodily through a small angle about an axis at the lower end thereof toward the platen 38, whereby pressure is exerted upon the platen by the selected character through a suitable ribbon to print the character upon the paper. It will be understood that the row selecting and character selecting movements may be accomplished substantially simultaneously, if desired, or in rapid succession, as may be found convenient or desirable, and that these movements are substantially completed just before the last part of the tilting or printing movement is completed.

It will further be understood that the type cylinder in its initial position as indicated in Fig. 4, is lowered to a point wherein the top of said cylinder is below the horizontal plane passing through the center of the platen, so that the printed letters on the paper are visible to the operator before and after a key is struck. It will further be understood that as the key is struck, the type cylinder is raised to the proper height to bring the selected character into a position substantially in a horizontal plane passing through the center of the platen whereby proper printing may be accomplished, and then on the release of the key, the type cylinder drops out of the way to render the printing readily visible. The ribbon 54 is normally out of the way or below said horizontal plane, but said ribbon is raised to the desired height to print through either half of the ribbon (black or red, depending on its adjustment), or the ribbon may be set to be maintained out of the way of the type for stencil printing purposes in a manner to be later described.

A well-known standard key board is preferably provided in my new machine, said key board consisting of keys 55 preferably arranged in four parallel rows. Each of the keys is operatively connected to the type cylinder to select the row and character, as well as to tilt the type cylinder to print the selected character by pressure. The escapement is also operated by the key to move the carriage, the ribbon being raised into printing position on the operation of the key. The ribbon may also be fed by well known mechanism connected to the key in a manner which is well understood, and hence need not be shown nor described.

Each of the keys 55 is secured to a key lever as 56. All of the key levers are suitably pivoted on the rod 57 (Fig. 4), the inner ends of said levers being suitably and differently shaped to act in the manner of cams for causing the se- 75

lecting movement of the type cylinder. It will be noted, however, that the key levers while normally in contact with the various selecting mechanisms are not secured thereto but are free to be swung about their pivots 57 when the machine is to be collapsed into its case.

Prior to the folding of the case, however, the front covering plate 147, which covers and protects the key levers and other operating mechanism, is swung about its hinge 148 into the dotted line position thereof shown in Fig. 4. Then, to swing the front section 14 and the keys and key levers into dotted line position on Fig. 4, the front section need merely be lifted, whereby the front wall 15 thereof engages the front portions of said levers, and swings said levers in a counter-clockwise direction about the pivot rod 57 and out of contact with the various operating means, said means being so disposed so as not to interfere with the type levers as they are swung into their collapsed position. There are preferably three operating or cam portions on each of the key levers, namely, the escapement operating portion 58, which also operates the cylinder tilting frame, the cylinder row selecting portion 60, and the cylinder character selecting portion 61.

The escapement mechanism for the carriage consists of the escapement operating portion 58 of the key lever (Fig. 4) which portion is suitably shaped to swing the escapement lever 62 in a counter-clockwise direction. Said escapement lever terminates at its forward end in an elongated supporting bar 63, to which is secured the universal escapement bar 64 extending across the machine. As shown in Figs. 3 and 4, the escapement lever 62 is pivotally mounted on the rod 65, which is in turn supported by a suitable bearing arm 66 projecting from the frame of the machine. The rearwardly projecting arm 67 of the escapement lever 62 terminates in a suitably rounded pin 68 passing through a suitable elongated or doubly bevelled opening 69 in the escapement pawl 70. Said pawl is pivoted to an upstanding ear or boss 71, extending from the frame of the machine, as by means of the screw 72. At its upper end, the escapement pawl 70 is provided with a pair of similar teeth 73 and 74 adapted to engage the respective ratchet wheels 75 and 76.

Said ratchet wheels are secured to the sleeve 77, which is internally threaded to engage the external threads of the carriage feed screw 40. The sleeve 77 is in turn mounted for rotation within the ears 79 extending from the frame, said ears preventing longitudinal or axial movement of the sleeve 77 by reason of the insertion of the ratchet wheels in the slot 80 thereof.

It will be seen that on the depression of any of the keys, the key lever 55 is rotated in a clockwise direction as viewed in Fig. 4. The terminal escapement operating portion 58 of the key lever serves to raise the escapement bar 63 and to rotate the escapement lever 62 together with the rod 65 in a counter-clockwise direction. The pin 68 is thereby lowered and the escapement pawl 70 rotated in a clockwise direction as viewed in Fig. 2 into the position of Fig. 2, wherein the tooth 74 has been withdrawn from the ratchet wheel 76 and the tooth 73 enters the space between the lowermost teeth of the ratchet wheel 75. However, between the time of the withdrawal of the tooth 74 and the entrance of the tooth 73 into the corresponding ratchet wheels, the carriage spring 50 becomes effective to move the carriage slightly toward the right

as viewed from the back of the machine or toward the left, as viewed from the front of the machine, a distance equivalent substantially to part of the space between printed letters, as is customary in the art. On the release of the key, the key is raised to its normal position by the weight of the escapement bar 64, said escapement bar dropping downwardly under its weight, or by the action of a suitable spring thereon, and thereby rotating the escapement lever 62 so that the end 68 thereof moves upwardly. The escapement pawl is thereby rotated in a counter-clockwise direction, as viewed in Fig. 2, the tooth 73 leaving the ratchet wheel 75 and the tooth 74 entering the ratchet wheel 76, whereby the ratchet wheels are permitted to rotate under the influence of the carriage spring 50. Rotation of the ratchet wheels causes rotation of the sleeve 77 in the stationary ears 79 and thereby advances the feed screw and the carriage longitudinally without rotation of said screw through the remaining distance between letters.

The carriage is also similarly moved by means of the spacing bar 81 to obtain the required space between words without printing. For this purpose, the space bar 81 is provided with the spacing lever 84, pivoted to the side walls 16 of the front section 14 as at 82, and is provided with a terminal hook or extension 83 operatively connected to the escapement operating mechanism. As best shown in Figs. 3 and 4, the connection comprises the link 85, guided in the boss 86 projecting from the frame 39 of the machine, and pivoted at its upper end as at 87 to the bent lever 88. Said lever, as will be noted from Fig. 3, extends from both sides of the machine, being operated by similar links 85, engaged by the spacing levers 84 at each end of the spacing bar. The lever 88 is furthermore secured to the escapement rod 65, whereby depression of the spacing bar causes rotation of said rod and consequent operation of the arm 67 of the escapement lever in the proper direction to operate the escapement, as has been above described in connection with the operation of the escapement by the keys.

As has been above indicated, depression of the proper key 55 selects the character to be printed and causes printing of the character by movement of the type cylinder 53. The various movements of the type cylinder caused by the depression and release of the key will now be described.

It will be noted that the initial position of the type cylinder is such that it is in its lowermost position as shown in Fig. 4 and that it is inclined slightly rearwardly at a very small angle to just clear the ribbon 54 and the platen 38. It will furthermore be understood that the type cylinder may occupy one of two initial positions, that is, for upper case printing, or for lower case printing, as has been previously explained, whereby the maximum angular rotation of the cylinder to select the last character of the row is less than 180°.

One of the movements of the type cylinder is that of selecting the proper row and carrying said row into printing position, which is preferably in the horizontal plane passing through the axis of the platen. The mechanism provided for this purpose includes the row selecting portion 60 of the type lever, said portion being suitably shaped and proportioned to swing the lever 91, which is pivoted on the rod 92 supported in the frame of the machine, through the proper distance to raise the type cylinder precisely the required amount. The lever 91 is provided with an arm 107 which

is perforated to receive and retain the rod 93. Said rod is preferably provided with two flat faces 94 and 95, respectively, and is arranged across the machine for engagement with the row selecting portions 60 of all of the type levers. The other arm of the lever 91 is connected to the link 96 as at 97, the upper end 98 of said link being pivoted (Fig. 5) to the lug 99 projecting from the sliding frame 100. Said sliding frame (Fig. 3) is provided with a pair of suitable upright grooves 101, into which enter the rear edges 102 of the tilting frame 103, whereby the sliding frame is guided in its movement vertically relatively to the tilting frame. Said sliding frame 100 is furthermore provided with a series of horizontal grooves 105 alternating with projections 106. The grooves receive the various type rows 89 and 90, while the projections enter the grooves 104 in the type cylinder between the rows of type and thereby serve to 20 guide the type cylinder in its rotation relatively to the sliding frame, but prevent relative longitudinal movement thereof, the projections 106 embracing the cylinder grooves 104 through an angle of more than 180° as will be seen from Fig. 3.

25 It will be seen that on the depression of a key 55, the row selecting portion 60 of the key lever 56 engages the flat face 94 and the lower corner of the rod 93 and raises said rod, thereby rotating the lever 91 about its pivot 92 in a clockwise direction as viewed in Fig. 4, until the rearwardly extending edge of the portion 60 comes into contact with the flat face 95, after which further rotation of the lever 91 is prevented. The link 96 is thereby raised through the lever 91 and the sliding frame 100 is also raised, carrying with it the type cylinder 53 until the proper row of the type cylinder is brought into printing position, the sliding frame 100 being guided at this time by the edge projections 102 which engage the grooves 101 of 30 said frame.

35 It will be understood that the row selecting portion 60 of the key lever is of such shape and proportion that it operates the lever 91 the exact distance required to select the desired row and that consequently, the shape and dimensions of said portion 60 differ on many of the key levers. The type cylinder 53 is made hollow, as shown in Fig. 5, and is guided by a suitable sleeve 108 inserted into the opening 109 therein. Said sleeve 40 is keyed to the type cylinder whereby rotation of the sleeve causes rotation of the type cylinder to select the desired character of a row in the manner soon to be described.

45 The means for selecting the particular desired character of any row will now be described. Said means includes the character selecting portion 61 of the key lever 56. Said portion is of the proper shape to engage the bar 110 which extends across the machine and which is connected to the rack 111. Said character selecting portion 61 is further of the proper shape to move the bar 110 the exact required distance to select the character corresponding to the particular key which is depressed. Bottom teeth 150 on the rack mesh with a spring-pressed pinion 151 supported by a shaft 152 for guiding the rack in its movement in a straight line path. The shaft 152 is suitably supported by the frame of the machine. The side teeth 112 of said rack are in constant mesh with the pinion 113 (Fig. 4), said pinion being mounted on the upright shaft 114 supported by the frame 30. At the upper end of said shaft is threaded the nut 115 which serves to maintain the spring 116 in place on the shaft.

5 The lower end of said spring abuts against the upper face of a clutch cylinder 117 which is keyed to the shaft 114 and which is provided with preferably four equally spaced clutch teeth 118 entering corresponding recesses 119 in the cam cylinder 120, which is loosely mounted on the shaft 114. Said cam cylinder is provided with a number, preferably four, equally spaced and similar cam surfaces 121, and terminates in the gear wheel 122.

10 It will be seen that on the rearward movement of the rack 111, through the intermediary of the bar 110, which is in turn operated by the portion 61 of the key lever 56, the pinion 113 and consequently, the shaft 114 and the clutch cylinder 117 thereon are rotated together with the cam cylinder 120 as a unit through the clutch tooth 118, the spring 116 serving to hold the clutch cylinder down on the cam cylinder. The gear 122 in turn meshes with the pinion 123 at the 20 lower end of the type cylinder sleeve 108 which, as has been explained, is keyed to the type cylinder. On the depression of the proper key 55, and the consequent rotation of the cam cylinder 120 and of the gear wheel 122 mounted thereon, 25 therefore, the pinion 123 is rotated, thereby rotating the sleeve 108 and also rotating the type cylinder the exact distance required to select the character to be printed. The gear 122 is preferably of twice the diameter of the pinion 123, 30 whereby rotation of the cam cylinder 120 through a quarter turn causes rotation of the type cylinder through a half turn or 180°, and thereby enables the operator to change from upper case to lower case characters, or vice versa. 35

This change, which I will call capitalization and decapitalization, is effected by means of either one of a pair of shift keys 124. Each of said keys is pivoted as at 82 to the side walls of the front section 14 and terminates in a hook or 40 extension 125. Said hook 125 engages the forward end of the shift lever 126, which is pivoted to an extension 127 of the frame as by means of the screw or pivot 128. It will be understood that the lever 126 extends symmetrically on both 45 sides of the machine and preferably terminates at its rear end in a loop 129 to clear the other mechanism (Fig. 3).

45 Carried by said loop, as by means of the screw 130, and nut 131, (Fig. 2), is a bevelled pin 132, 50 which is normally arranged vertically above one of the cam surfaces 121 of the cam cylinder 120. It will be seen that on the depression of the shift key 124, the shift lever 126 is rotated about its pivot 128 in a counter clockwise direction as 55 viewed in Fig. 4, thereby carrying the bevelled pin 132 down into forcible contact with the adjacent cam surface 121, and thereby causing rotation of the cam cylinder and of the gear 122 thereon through an angle of 90° backwardly. The gear 60 122 in turn rotates the pinion 123 through an angle of precisely 180° and thereby reverses the position of the characters on the type cylinder to a diametrically opposite position, that is, the positions of the upper case and lower case characters on the type cylinder become interchanged. Backward rotation of the cam cylinder 120 does not effect any rotation of the pinion 113 since said cam cylinder is loose on the shaft 114, the tooth 118, however, becoming disengaged from 70 the clutch recess in the cam cylinder, since the pinion 113 is locked by the rack 111 which engages and is stopped by the portions 61 of the various key levers and which cannot therefore move at this time. 75

The clutch tooth 118 drops into the next clutch recess 119 of the cam cylinder at the completion of the backward rotation, to accurately position the gear 122 and the cam cylinder in their initial 5 positions, whereupon the operator may continue typing either capital or small characters as the case may be. To change from capital letters to small letters or from small letters to capital letters again, the shift key is again depressed, 10 thereby again rotating the cam cylinder 120 a quarter turn and rotating the type cylinder a complete half turn.

The row selecting and character selecting mechanism having been described, it now remains to describe the noiseless printing movement of the type cylinder. Said movement is accomplished by means of the same portion 58 of the key lever, which operates the escapement. Said portion, after operating the escapement, engages the roller bar 133, mounted on the shaft 134, and carrying the toggle member 135. At its rear end, the toggle member is connected to one end of the toggle link 136, the other end of which is connected as at 137 to the tilting frame 103. 20 The forward end of the toggle member 133 is pivotally secured to a suitable extension on the frame. 25

It will be seen that as the key 55 is depressed, the portion 58 being suitably shaped to raise the roller bar 133 and thereby to straighten the toggle members 133 and 136, causes the tilting frame 103 to move rearwardly about the pivot 139 by means of which the tilting frame is pivoted at its lower end to the frame of the machine. 30 The tilting frame together with the sliding frame 100 and the type cylinder carried thereby are thereby pressed rearwardly through a small angle, the character selected being in the proper position to print through the ribbon 54 during 35 the last part of the tilting movement by pressure and not by a blow, thereby making the printing operation noiseless. The extension 59 of the key lever serves to limit the lowermost position of the roller bar 133.

45 At about the same time, the ribbon 54 is raised the proper distance to be interposed between the selected character and the platen. Said ribbon 54 is mounted on a pair of suitable spools as 40 in a well known manner, suitable mechanism not shown but well understood, being provided to feed the ribbon intermittently on the depression of each key. The ribbon is carried in a suitable ribbon frame 141 which is raised and lowered on the depression and release of the key. 50 The amount that the ribbon is raised can be adjusted so that the upper half or the lower half of the ribbon comes into operation to print different colors such as red or black, as may be desired, or the ribbon may be so adjusted that no printing 55 is done as for example, when it is desired to do stencil work.

Toward this end, the frame 141 is connected at its lower end to a pair of levers 142 which are pivoted as by means of the pin 143 to the eccentric 65 144 (Fig. 4). Said eccentric is rotatably mounted in a suitable extension of the frame of the machine and is rotated within its supporting frame by means of the ribbon adjusting handle 145. The ribbon operating lever 142 is provided with 70 a suitable operating portion 146 adapted to be engaged by the rear portion of the universal bar 64 whereby said lever is raised about its pivot 143 the proper distance to raise the ribbon 54 into its required operative position on the operation of a key 55. When the handle 145 is rotated

to the upper dotted center line position of Fig. 4, the pivot pin 143 is lowered and the operating portion 146 of the lever 142 is thereby carried nearer to the universal bar 64. In the adjusted position of the handle 145 just described, the lever 142 being in its nearest position relatively to the universal bar 64, its movement by said bar begins sooner and the ribbon 54 is thereby raised through a greater height than in any of the other adjusted positions of said handle. The 10 lower part of the ribbon being usually colored red, the characters will print red on the paper inserted about the platen. Similarly, when the handle 145 is in the full line position shown in Fig. 4, the lever 142 is at a slightly greater distance from the bar 64 and is thereby later engaged by said bar and therefore raised a less distance. The upper part of the ribbon therefore comes into operation and prints black in the usual way. When it is desired that the ribbon 20 be moved out of the way so as not to print at all, then the handle 145 is shifted into the lowest dotted center line position of Fig. 4, wherein the pin 143 is in its highest position and the universal bar 64 is ineffective to raise the ribbon a sufficient 25 distance to print at all.

The operation of my improved machine has been fully described above in connection with the description of the various parts thereof and hence need not be repeated. It need merely be 30 said that the machine together with the type levers may be folded for ready portability, by first swinging the cover 145, which covers the various type levers and inner operating mechanisms, upwardly about the pin 148 into the position shown 35 by the dotted lines 149 of Fig. 4. The front section 14 may then be swung upwardly about the hinge 17, carrying the type bars, the spacer bar and the shift keys upwardly and into the dotted line positions of Fig. 4. Thereafter, the rear section 25 40 may be swung upwardly about its hinge 21 and secured to the front section. To unfold the machine ready for operation, the steps just described are reversed.

It will be seen that I have provided simple 45 and efficient mechanism, eliminating the numerous type bars now customarily used in typewriters, for selecting characters and causing them to print by pressure and therefore substantially noiselessly, which mechanism necessitates a 50 minimum number of parts and thereby causes the machine to be light and readily portable. It will further be seen that I have provided effective means well adapted to meet the severe requirements of practical use. 55

While I have shown and described certain specific embodiments of my invention, it will be understood that I do not intend to limit myself thereto but desire to claim my invention as broadly as may be permitted by the state of the prior 60 art and the scope of the appended claims.

I claim:

1. In a typewriter, a type cylinder, a plurality of vertically spaced circumferential rows of type on said cylinder, each of said rows carrying 65 lower case characters on one-half thereof and upper case characters on the other half thereof, means including a key for rotating the cylinder to select upper or lower case characters, a key board including keys, a pivoted key lever for each 70 of said keys, said key lever being provided with a series of shaped operating portions, row selecting mechanism operatively connected to the type cylinder, character selecting mechanism operatively connected to the type cylinder, each 75

of said mechanisms being arranged normally to contact with one of the operating portions of the key lever and to be operated on the depression of a key, a platen spaced from the type cylinder a distance less than the radius of the latter, and means normally engaging another operating portion of the key lever for tilting the type cylinder toward the platen through a small angle and operated on the depression of the key for printing the selecting character by pressure and noiselessly, said type cylinder being normally arranged below the center line of the platen to normally expose the writing portion of the platen to view.

2. In a typewriter of the character described, a type member provided with a plurality of rows of type, each of said rows containing a set of upper case characters and a set of lower case characters, means for rotating the member through an angle of 180° to shift the member from the position for printing a selected one of one set of characters to the position for printing a selected one of the other set of characters, a key, provided with three shaped operating portions, means operated by one of the operating portions of the key and operatively connected to the member for selecting a row, means operated by another of said portions for selecting a character from said row, and means operated by the third portion for tilting said member to cause the selected character to print.

3. In a typewriter, operating keys, a type cylinder carrying a plurality of rows of type, means operated by a key for moving said cylinder axially to select a row, means operated by the key for rotating the cylinder to select a character in the selected row, and means operated by the key for tilting said cylinder rearwardly to carry the selected character into printing position, said last-mentioned means including a toggle, and means for applying straightening pressure to the joint of the toggle.

4. In a typewriter, a type cylinder provided with a plurality of vertically spaced rows of type, a slidable frame supporting said cylinder for axial movement and for rotation therein, a tilting frame supporting the slidable frame, operating keys, means operatively connecting the keys to the cylinder for rotating the cylinder through a predetermined angle on the operation of a key, means operatively connecting the keys to the slidable frame for sliding said frame and the cylinder axially through a predetermined distance on the operation of a key, and a toggle connection between the keys and the tilting frame for tilting said frame to carry the cylinder into printing position.

5. In a typewriter, a type cylinder carrying a plurality of vertically spaced rows of type, a ribbon arranged rearwardly of the cylinder, key operated means for moving the cylinder axially to select a row, for rotating the cylinder to select a character in the selected row and to tilt the cylinder toward the ribbon to print the selected character, key operated means for raising the ribbon into printing position, and a series of keys each provided with a plurality of integral shaped portions for operating said cylinder moving, rotating and tilting means and said ribbon raising means on the depression of the key.

6. In a typewriter, a type cylinder provided with a plurality of vertically spaced rows of type, key operated means for selecting a row, for selecting a character from said row and for putting pressure on the character in printing position, a ribbon arranged rearwardly of the type

cylinder and normally below printing position, key operated means for raising the ribbon into printing position and permitting the ribbon to drop into its initial position after the selected character has been printed therethrough, and a series of keys, each provided with a plurality of integral shaped portions for operating said row selecting, character selecting and character pressing means and said ribbon raising means on the depression of the keys.

7. In a typewriter provided with a plurality of vertically spaced rows of characters, means for selecting a character from a row, and key operated means for moving the rows through a slight angle in a vertical plane to cause the selected character to print noiselessly by pressure, including a toggle and a key portion engaging the joint of the toggle to apply straightening pressure thereto.

8. In a typewriter, a type cylinder carrying a plurality of vertically spaced rows of type, one-half of each of said rows containing upper case characters and the other half containing lower case characters, means for supporting said cylinder for rotation about its axis, for axial movement thereof and for the tilting thereof bodily in a vertical plane, keys carrying upper case and lower case indicia thereon, means operatively connecting the keys to the cylinder to select a character and to move the selected character into printing position, and capitalizing and decapitalizing means for rotating the cylinder through an angle of 180° comprising a shift key, a lever operated by said key, a cam follower near one end of said lever, a cam rotated by said follower through a predetermined angle on the depression of said shift key, and gearing connecting the cam to the cylinder to rotate the cylinder.

9. In a typewriter, a member carrying a plurality of vertically spaced rows of type, operating keys, pivoted key levers carrying said keys, said key levers being provided with a series of operating projections, means adapted to be engaged by one of said projections and operatively connected to the type carrying member for moving said member axially to select a row, means adapted to be engaged by another of said projections and operatively connected to the type member to move said type member for selecting a character from the selected row, means adapted to be engaged by another of said projections and operatively connected to the member for tilting said member into printing position including a toggle.

10. In a typewriter, an axially movable, rotatable, and tiltable member, type characters on said member, key levers, a series of operating portions on said key levers, means arranged normally in the path of one of said operating portions to move the member axially, means arranged normally in the path of another of said portions to rotate the member, means arranged normally in the path of a third portion to tilt the member, a carriage, an escapement feed for the carriage, and means adapted to be engaged by one of said portions to operate said escapement.

11. In a typewriter, a type cylinder carrying a plurality of vertically spaced rows of type, one-half of each of said rows containing upper case characters and the other half containing lower case characters, a frame embracing the cylinder between said rows through an angle of less than 360° and adapted to support the cylinder for rotation about the axis thereof, and capitalizing

and decapitalizing means for rotating the cylinder through an angle of 180° comprising a shift key, a lever operated by said key, a grooved cam rotated by said lever through a predetermined angle on the depression of said key, and means for operatively connecting the cam to the cylinder to rotate the cylinder.

12. In a typewriter, a type cylinder, an annular row of type on said cylinder, one-half of said row containing upper case characters and the other half containing lower case characters, and capitalizing and decapitalizing means for rotating the cylinder through an angle of 180° comprising a shift key, a lever operated by said key, a toothed member on the lever, a grooved cam adapted to be rotated by the toothed member through a predetermined angle, and means for operatively connecting the cam to the cylinder to rotate the cylinder.

13. In a typewriter, a type cylinder, key levers, a single pivot bar for said levers, a series of operating portions each of predetermined shape on said key levers, means arranged normally in the path of one of said operating portions to move the cylinder axially, means arranged normally in the path of another of said portions to rotate the cylinder, and means arranged normally in the path of a third portion to tilt the cylinder, said portions being shaped to move the cylinder through a predetermined distance.

14. In a typewriter, a type carrying cylinder, a series of key levers, a single pivot bar for said levers, a cylinder tilting portion on each of said key levers, a cylinder rotating portion on each of said levers, a cylinder raising portion on each of said levers, and means arranged in the path of each of said portions and operatively connected to the cylinder for effecting predetermined movement of the cylinder, the shapes of said portions determining the extent of said movement.

15. In a typewriter, a pivoted key lever, an operating portion thereon, a link pivoted at one of its ends and arranged in the path of said operating portion, a second link connected to the other end of the first-mentioned link and arranged slightly out of alignment therewith, a pivoted frame pivoted to the second link, and a type cylinder carried by said frame, said links forming a toggle joint whereby depression of the key straightens said joint to tilt the frame and to move the cylinder through a small angle into printing position.

16. In a typewriter, a type cylinder, a pivoted frame supporting said cylinder, and means for tilting said frame through a small angle to cause said cylinder to print by pressure, comprising a first link pivoted at one end of said link, a roller bar carried by said link, a second link connecting the frame and the first link, a series of key levers and an operating portion on each of said levers adapted to engage said roller bar to straighten said links relatively to each other and thereby to exert tilting pressure upon the frame.

17. In a typewriter of the character described, a type member provided with a plurality of rows of type, each of said rows containing a set of upper case characters and a set of lower case characters, means for rotating the member through a predetermined angle to shift the member from the position for printing a selected one of one set of characters to the position for printing a selected one of the other set of characters, a key provided with three shaped operating portions, means operated by one of the operating portions of the key and operatively connected to the member for selecting a row, means operated by another of said portions for selecting a character from said row, and means operated by the third portion for tilting said member to cause the selected character to print.

18. In a typewriter, a type cylinder, key levers, a series of operating portions each of predetermined shape on said key levers, means arranged normally in the path of one of said operating portions to move the cylinder axially, means arranged normally in the path of another of said portions to rotate the cylinder, and means arranged normally in the path of a third portion to tilt the cylinder, said portions being shaped to move the cylinder through a predetermined distance.

19. In a typewriter, an axially movable, rotatable, and tilttable member, type characters on said member, key levers, a series of operating portions on said key levers, means arranged normally in the path of one of said operating portions to move the member axially, means arranged normally in the path of another of said portions to rotate the member, means arranged normally in the path of a third portion to tilt the member, a carriage, an escapement feed for the carriage, and means adapted to be engaged by one of said portions to operate said escapement.

ROBERT G. CLARK.
